UNITED STATES PATENT OFFICE.

LESTER H. FRONK, OF SALT LAKE CITY, UTAH.

LOUD-SPEAKER UNIT.

Application filed April 23, 1926. Serial No. 104,080.

This invention relates to improvements in loud speaker units for reproducing electrically carried sound waves.

An object of the invention is to provide a special construction for the loud speaker unit in which a specially shaped permanent magnet is used with independent pole pieces forming a housing for an electric coil and an armature to be operated thereby in which a substantially uniform flux flows at both magnetic poles of the coil and the permanent magnet in order to produce an efficient operation of the armature which is connected to a suitable diaphragm structure from which the sound reproduction is obtained which has been found to be of a strong and mellow character.

A further object of the invention resides in the special construction of the coil mounting with the method of suspending the armature in the coil for free oscillating movement in order to obtain efficient sound reproduction with weak currents, and which will prevent sound distortion when reproducing sound with strong currents and considerable volume.

The invention further comprehends the provision of a special diaphragm housing and mounting in order to properly center the diaphragm in its mounting and prevent it from being set too tight, off side, or in other than a very level position.

The invention comprehends numerous other objects residing in the details of construction and the relation of the parts to permit the ready and convenient assembly thereof in order to produce an assembled construction at a substantially low cost, which are all pointed out more particularly in detail in the following description and in the claims directed to a preferred form of construction, it being understood, however, that various changes in the size, shape and relation of these parts may be made without departing from the spirit and scope of the invention as herein set forth.

In the drawings forming part of this application:—

Figure 1 is a plan view of the assembled figure unit.

Fig. 2 is a side elevation thereof.

Fig. 3 is a vertical sectional view taken on the line 3—3 of Fig. 1.

Fig. 4 is a vertical sectional view taken on the line 4—4 of Fig. 1.

Fig. 5 is an enlarged horizontal sectional view taken on the line 5—5 of Fig. 4.

Fig. 6 is a perspective of one of the pole pieces.

Fig. 7 is a sectional view taken on the line 7—7 of Fig. 5.

1, indicates the plate member and support for the assembled unit of annular form and having an annular recess formed in the lower face thereof indicated at 2 from the edge portion of which depends the annular flange 3 adapted to seat within the annular recess 4 in the cap 5. The plate member 1 is suitably secured to the cap member 5 by screws 6 or the like and is adapted to secure the diaphragm 7 in operative position in the recess 4 of the cap member by engagement with the washers 8 of ring shape which are superposed on the opposite faces of the diaphragm as clearly shown in Fig. 3. With this construction the diaphragm 7 is respectively centered in the recess 4 and held against movement by the plate member compressing the washers or packing rings 8 which are preferably of rubber or similar material and provide a rigid mounting for the edge portion of the diaphragm.

The packing ring placed between the diaphragm 7 and the cap member 5 is seated in an annular groove 9 in the recess 4 so that it will be firmly retained in place during the operation of the diaphragm. The cap member 5 is provided with a sleeve extension 10 threaded at the outer end to which an amplifying horn may be attached for obtaining well known results in the art. The base plate member 1 is provided with a plurality of holes 11 providing communication with the chamber or recess 2 formed in the lower face of the plate member to permit free passage of air into the chamber so that the air that is set in motion by the vibration of the diaphragm may be equalized, and thereby more efficiently and perfectly reproduce sound by the operation of the diaphragm without distortion.

A diaphragm pin 12 connects the diaphragm 7 with the armature 13 which is of substantially rectangular form as shown in Fig. 5. The diaphragm pin 12 is connected to one end of this rectangular armature while the central portion thereof is provided with a suitable wire pivot mounting 14 between a pair of clamp members 15. This wire 14 is formed with a bight in the central portion as

shown at 16 in Fig. 7, while the end portions extend thru openings in the armature to the opposite face and then along the opposite face of the armature for connection to the clamp members 15.

This wire is suitably soldered to the armature in its length of contact therewith, and extends through openings in the central offset portion of the clamp members as clearly shown in Fig. 5, having the free ends extended laterally and suitably soldered or otherwise secured to these clamp members.

These clamp members have laterally extending ends 17 which engage and into which are attached side supporting members 18 for the coil winding 19. A pair of plates 20 are secured to the opposite faces of the clamp members 15 and between the end supporting plates 20 for the coil 19 to cooperate with the clamp members 15 to form a housing for the armature 13 in which it is freely operable. The plate members 20 in addition, serve to retain the end supporting plates 18 in rigid engagement with the lateral ends 17 of the clamp members so that a complete coil supporting form is provided for the coil 19. A suitable insulating covering is preferably wrapped around the plates 20 and the clamp members 15 on which the coil 19 is wound while the completed coil is covered with a suitable insulating and protecting covering 22 as more particularly shown in Figs. 5 and 7.

The base plate 1, the cap member 5, the diaphragm pin, armature, clamp members, plates 20, and end plates 18 for supporting the coil 19, are all preferably formed of non-magnetic metal such as glass, copper, or the like having the desired qualities for the purposes for which it is used. The armature 13 is preferably formed of silicon steel.

The completed coil structure and armature as above described are received and housed by a pair of pole pieces 23 and 24 respectively, which form lower and upper pole pieces respectively and are of duplicate construction as clearly illustrated in Fig. 6. These pole pieces include plate portions 25 from the opposite sides of which are laterally extending flanges 26 arranged in spaced parallel relation and having projections 27 from the central portions of their ends as clearly shown in Fig. 6. These pole pieces are mounted in opposed relation in the assembled position of the parts as shown in Figs. 2 and 4 and have their transverse centers coincident with the central longitudinal plane of the armature 13, as illustrated in Fig. 2.

The projections 27 from the end of the lateral flanges 26 extend into close proximity with each other and in close but spaced parallel relation with opposite sides of the armature 13 as may be clearly ascertained in Figs. 2 and 4. The end supporting plates 18 and the assembled coil 19 as above de-

scribed are received between the flanges 26 and entirely housed thereby as shown in Fig. 2, the base portions 25 engaging the opposite edges of the end plates 18 and rigidly mounting the coil assembly in position between these pole pieces.

The ends of the pole pieces are formed with openings 28 which slidably fit over the posts 29 mounted on the base plate 1 and rigidly secured in assembled position by means of nuts 30 threaded on these posts 29. This pole piece structure, it will be seen, provides a rigid assembly and mounting of the coil and its supporting structure together with the armature supported in the coil supporting structure so that a simple and efficient mounting is provided for these parts.

A permanent magnet 31 of special design is employed with this loud speaker unit construction which is formed with an arcuate portion 32 of substantially semi-cylindrical shape terminating at one side in the straight end 33 which is tangential to the end of the semi-cylindrical portion 31 while the opposite end of the semi-cylindrical portion merges into the straight portion 34, parallel with the end 33, and which terminates in the laterally extending end 35. The end 35 extends toward end 33 and substantially at right angles thereto and offset relative to the end thereof as can be clearly ascertained by an examination of Fig. 4.

The central portion of the end 35 of the permanent magnet is formed with a V-shaped recess 36 to provide a passage for the diaphragm pin 12, as clearly shown in Figs. 4 and 5. The permanent magnet is mounted on the base plate 1 with the end 35 in contact therewith having the end portion thereof positioned in contact with the lower pole piece 23 and centered so that the central portion of the magnet is centered with respect to the armature. In this position of the magnet, the end 33 will overlap the pole piece 24 and have the inside surface of the end portion contacting with said pole piece 24 at the opposite side from the point of engagement of the end of the portion 35 with the pole piece 23.

A securing bar 37 of suitable non-magnetic metal is positioned transversely across the end portion 35 of the permanent magnet 31 and secured at its end to suitable posts 38 mounted in the base plate 1 by the nuts 39 threaded thereon. This form of mounting provides an efficient clamp to permit the ready attachment and adjustment of the pole piece with respect to the armature and coil mounting structure as well as the pole pieces 23 and 24.

One of the flanges 26 on each of the pole pieces 23 and 24 and the flange positioned adjacent to the diaphragm pin 12 is formed with a groove 40 in the central portion to

provide accommodation in cooperation with the recess 36 for the mounting and adjustment of the diaphragm pin, while the central portion of the plate member 1 is provided 5 with a central opening 41, through which the diaphragm pin passes and operates.

With the above described construction, it will be understood that the suspending structure for the diaphragm 13 as clearly 10 illustrated in Figs. 5 and 7 provides a tension on the diaphragm 13 and the pin and diaphragm 7 of such a character that it will not be subject to rattles or other looseness while the magnetic flux of the permanent 15 magnet 31 will have a complete circuit through the pole pieces and will be concentrated at the gaps between these pole pieces at the ends of the projections 27 where this field will exert its maximum force on the 20 armature 13 at the opposite ends thereof.

In being properly centered between the flanges 26 of these pole pieces, it will be seen that the action of both the south and northern poles of the permanent magnet will 25 equalize at the gaps between the pole pieces and exert a substantially even and equal pole on the armature. This equalized magnetic flux of both north and south polarity operating and at equal distances from the pivotal 30 mounting of the armature provides for the easy and efficient operation of the armature through variations of this flux which occur upon the energization of the coil 19. By positioning the coil between these pole pieces in the manner illustrated and described above, it will be seen that the north 35 and south magnetic poles of the coil will occur at the flanges 26 of the pole pieces so that the flow of magnetic flux across the gaps between the ends of the pole pieces 23 and 24 will directly operate the armature. In this way, substantially weak 40 currents flowing in the coil 19 will cause a fluctuation in the flux operating the armature, and thereby produce the reproduction 45 of the feeble currents in sound waves which have been found in the practical operation of the device constructed as shown in the drawings to produce a substantial volume of 50 sound for these weak currents. This result is obtained through this balanced action of the magnetic fields on the opposite ends of the armatures and on opposite polarity and through the relation of the pole pieces to the 55 ends of the coil 19.

The variation of the flux of opposite polarities increases the power to operate the armatures to substantially double what it would ordinarily be in the case where the 60 flux at only one pole of the magnet is effected

to directly operate the diaphragm or armature. This equalization of the flux of the permanent magnet on the opposite ends of the armature together with the pole of the coil being at the flanges 26 of the pole pieces 65 for directly varying the field acting on the armature is found to result in a more perfect reproduction of the entire audible range of sound waves, with substantially no distortion and through the balancing action to 70 eliminate mechanical vibrations from transmission and reproduction by the diaphragm.

From the above description, it will therefore be understood that the diaphragm mounting, the armature suspension with the 75 coil assembly, the permanent magnet structure, and the manner of assembling the several parts to produce the operations above set forth form the novel features of this invention.

Having thus described my invention, what I claim as new is:—

1. An armature mounting for loud speaker units, comprising a support, a pair of clamping members secured in spaced parallel relation to said support, an armature positioned between said clamp members, and a wire member rigidly secured to said armature in its central portion and having the terminal thereof rigidly secured to said 80 clamp members.

2. An armature suspension and coil support, comprising a supporting means, a pair of end plates mounted in said spaced parallel relation in said supporting means, a pair 85 of clamp members mounted in spaced parallel relation in opening said end plates, a pair of plate members mounted on opposite sides of said clamp members and positioned between the end plates operable to hold said 90 end plates in spaced relation, said plate members forming an armature housing with said clamp members, an armature suspended in the armature housing between said clamp 95 members, and a coil mounted on the plate 100 members and clamp members around said armature housing and between said end plates.

3. A permanent magnet for loud speaker units comprising an elongated flat bar member, formed with a semi-cylindrical portion, the end portions extending in parallel relation from said semi-cylindrical portion and terminating in unequal lengths, the longer extension having the terminal thereof 110 formed with a lateral extension terminating in substantially the central plane between said extensions.

In testimony whereof I affix my signature.
LESTER H. FRÖNK.
